CLAIM

The ornamental design for a network hub, as shown and described.

DESCRIPTION

FIG. 1 is a top front perspective view of a network hub showing our new design;

FIG. 2 is a rear bottom perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The broken lines in the figures illustrate portions of the network hub that form no part of the claimed design.

1 Claim, 7 Drawing Sheets
